CLAIM

The ornamental design for a three-man water sled, as shown and described.

DESCRIPTION

FIG. 1 is a top plan view of a three-man water sled showing my new design;

FIG. 2 is a side elevational view thereof, the opposite side elevational view being a mirror image of that shown;

FIG. 3 is a front elevational view thereof;

FIG. 4 is a rear elevational view thereof; and,

FIG. 5 is a bottom plan view thereof.
